UNITED STATES PATENT OFFICE.

FRANK HENRY PETERMAN, OF NEW YORK, N. Y., ASSIGNOR TO HIMSELF AND FRANK J. FREDERICKS, OF SAME PLACE.

RAISIN-SEEDER.

SPECIFICATION forming part of Letters Patent No. 666,974, dated January 29, 1901.

Application filed February 17, 1900. Serial No. 5,594. (No model.)

To all whom it may concern:

Be it known that I, FRANK HENRY PETERMAN, a citizen of the United States, and a resident of the city of New York, borough of Manhattan, in the county and State of New York, have invented a new and Improved Raisin-Seeder, of which the following is a full, clear, and exact description.

The invention relates to raisin-seeders in which the raisins are pressed upon impaling-pins to force the seeds out of the pulp.

The object of the invention is to provide a new and improved raisin-seeder arranged to readily force the seeds out of the pulp without unduly tearing the latter and to readily remove the pulp from the impaling-pins and to clean the latter to insure at all times a proper impaling of the raisins upon the pins.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement. Fig. 2 is a rear end elevation of the same with parts removed and parts in section. Fig. 3 is a plan view of the feed-hopper and adjacent parts with part broken out. Fig. 4 is a sectional plan view of the same. Fig. 5 is a plan view of a modified form of the same. Fig. 6 is a sectional side elevation of a modified form of the improvement, and Fig. 7 is a perspective view of the seed-remover for removing the seeds from the impaling-pins.

The improved raisin-seeder illustrated in Figs. 1, 2, 3, and 4 is mounted on a suitably-constructed frame A, in which is journaled a cylinder-shaft B, connected by a gear-wheel B' with a pinion B², secured on a driving-shaft B³, likewise journaled in the main frame A and having a pulley B⁴, engaged by a belt connected with other machinery for imparting a rotary motion to the said shaft B³, the motion of the latter being transmitted by the pinion B² and the gear-wheel B' to the cylinder-shaft B to rotate the latter and with it the impaling-pin cylinder C in the direction of the arrow a'. The impaling-pin cylinder C is secured on the shaft B and has its peripheral surface covered by impaling-pin plates D', carrying impaling-pins D, arranged in longitudinal rows and spaced apart in such a manner as to exclude the seeds of raisins E or to penetrate the pulp and separate the pulp from the seeds, as hereinafter more fully described. The plates D' are secured by screws or other means to the peripheral surface of the cylinder C to permit of conveniently removing any one of the plates and repairing the pins whenever necessary.

The raisins E to be seeded are contained in a hopper F, discharging the raisins upon an endless compartment apron or belt G, made of rubber or other suitable material and having compartments or pockets at its outer face, each for receiving and containing a single raisin, said apron forming the bottom of the hopper F, the discharge end being directly over the top of the impaling-pin cylinder C, as will be readily understood by reference to Fig. 1.

In order to prevent more than one raisin from occupying a pocket or compartment at a time, a brush H is provided, journaled in the sides of the hopper F and extending transversely of the apron G at the top run thereof, and under the discharge end and over the brush H is arranged a comb I, secured to the front of the hopper F and extending rearwardly over the top and rear portion of the brush H to prevent raisins from passing over the brush and collecting on the same between the top of the brush and the front of the hopper F. The comb I may be solid, as illustrated in Figs. 1 and 3, or it may be in the shape of fingers, as illustrated in Fig. 5.

On the front or discharge end of the hopper F is arranged a row of transversely-extending small auxiliary hoppers F', in alignment with the pockets or compartments of the apron G, so that the raisins will not roll one on top of another in discharging from the hopper or apron. Previously to the raisins dropping from a pocket or compartment upon the impaling-pins D the latter are engaged

by a pulp-remover in the form of a fabric J, such as open-mesh woven fabric cloth—ordinary cheese-cloth, for instance—unwinding from a roll J', journaled in suitable bearings 5 carried by the frame A. The cloth J after unwinding from the roll J' is passed under a series of disks J², extending between the longitudinal rows of impaling-pins, so that the cloth J in passing under said disks is 10 pressed by the latter upon the impaling-pins near the bottom thereof—that is, upon the top of the impaling-pin plates D'—as will be readily understood by reference to Fig. 1. The disks J² are loosely journaled on a shaft 15 carried by the frame A, and said disks are located under the rear end of the apron G, so that the cloth J is pressed in engagement with the pins previous to the raisins passing upon the pins at or near the top of the impaling-pin cylinder C. The cloth thus pressed upon the impaling-pins by the disks J² remains on the latter until it nearly reaches the bottom of the cylinder, when the cloth is 20 passed from the pins under a roller J³, to then 25 wind up on a roll J⁴, having its shaft J⁵ mounted to turn in suitable bearings carried by the frame A. On the shaft J⁵ is held a friction-pulley K, connected by a belt K' with suitable machinery, so as to rotate said friction-pulley and said shaft J⁵ and roll J⁴ to wind 30 up the cloth without danger of slack occurring in the cloth after it leaves the impaling-pins and passes under the roller J³ to the roll J⁴.

The raisins, evenly distributed by the 35 pocket or compartment-apron G upon the impaling-pins, can be successively passed upon a number of elastic rollers L L' L² L³ L⁴, journaled in adjustable bearings held on the main frame A and driven by suitable gear-wheels 40 from the main driving-shaft B³, so that all the rollers rotate in unison and also in unison with the impaling-pin cylinder C. Now as the raisins are carried under the roller L they are pressed upon the impaling-pins D, and 45 the next roller L', on account of being closer to the pins, presses the raisins still farther upon the pins. The succeeding rollers L² L³ L⁴ still further press the raisins upon the impaling-pins, so that the seeds are forced out 50 by the pins through the skin of the pulp, and as the seeds can readily embed themselves on the rollers L³ L⁴ it is evident that the skin of the pulp is opened sufficiently for the passage of the seeds, thus avoiding serious injury to 55 or tearing of the pulp. The seeds adhering to the outer ends of the pins and the pulp are held to the pins above the cloth J after passing the roller L⁴, and then the seeds are removed from the impaling-pins by a revolving 60 stripper N, having plates N' arranged spirally in a transverse direction and preferably made of rubber, so as to brush the seeds off the impaling-pins. Next to the revoluble stripper N is arranged a second stripper O, 65 in the form of a comb, the teeth of which extend tangentially to the peripheral surface of the impaling-cylinder, the points of the comb

being in close proximity to the points of the impaling-pins, so that the seeds are forced out of the impaling-pins without the teeth of the 70 comb injuring the pulp still held on the impaling-pins D, between the outer ends thereof and the cloth J. The pulp carried along by the impaling-pins is finally pushed out of the latter by the cloth J as the latter leaves 75 the impaling-pins and passes under the roller J³, (see Fig. 1,) it being understood that as the cloth passes off the pins it strips the pulp off the pins and causes the pulp to drop and be deflected by a deflector P into a box Q, 80 located below the bottom of the cylinder C between the deflector P and the roller J³. A box Q' below the strippers N and O serves to receive the raisin-seeds.

From the foregoing it is evident that the 85 cloth or fabric J forms a fruit or pulp removing or stripping device, and as the cloth slides on the pins when leaving the same at the bottom of the cylinder it is evident that the cloth cleans the pins by removing any juice 90 or other matter that may have passed on the pins when pressing the raisins, as above explained. When the cloth J has been completely unwound from the roll J' and wound up on the roll J⁴, then a new roll of cloth is 95 substituted and the old piece is washed, so as to be again ready for further use on the machine. If desired, however, an endless piece of cloth J may be used—as shown, for instance, in Fig. 6—and passed through a washing liquid in a tank R after the pulp is removed from the pins and previous to the cloth passing back upon the cylinder. For this purpose the cloth after leaving the roller J³ passes up over a roller S and then down and 105 under rollers S', journaled in the tank R below the surface of the liquid therein, and then the cloth extends upward between two pressing-rollers S² for pressing out surplus liquid contained in the cloth and taken up 110 during its passage through the liquid in the tank R. The cloth is cleaned during its passage through the liquid in the tank R, and the clean cloth after leaving the pressing-rollers S² is passed under a slack-taking-up 115 roller T, and then extends upward and passes over the roll J', and then downward and under the disks J², to be again pressed upon the impaling-pins. The slack-taking-up roller T is 120 journaled in bearings fitted to slide vertically in a guideway T', and the bearings are pressed by a spring T², so as to hold the roller T in position to take up all slack in the cloth.

The pocket or compartment apron G passes over two rollers G' G², of which the roller G² 125 is preferably driven by suitable gearing U from the upper pressing-roller L, as indicated in Figs. 3 and 4. A clutch U' is used in connection with this gearing to throw the roller G² out of gear, so as to stop the feeding of 130 the raisins whenever desired. The brush H is preferably driven from the roller G² by suitable gear wheels and chains V, as indicated in Figs. 2 and 4.

Having thus fully described my invention, I claim as new and desire to secure by Letters Patent—

1. A raisin-seeder having a revoluble impaling-pin cylinder carrying impaling-pins in circumferential rows, a woven fabric for engaging said impaling-pins, and disks extending between the rows of impaling-pins to press the fabric upon said impaling-pins, substantially as shown and described.

2. A raisin-seeder having a revoluble impaling-pin cylinder, an endless woven fabric, and guides for guiding the fabric to and from a portion of said cylinder, to engage the impaling-pins thereon and to travel therewith during a part of the revolution of the cylinder, substantially as shown and described.

3. A raisin-seeder having a revoluble impaling-pin cylinder, an endless woven fabric, guides for guiding the fabric to and from a portion of said cylinder, to engage the impaling-pins thereon and to travel therewith during part of the revolution of the cylinder, and a deflector between the impaling-pins and the guides, for disengaging the fabric from the impaling-pins, said deflector serving to

deflect the removed pulp to a receiving-box, as set forth.

4. In a raisin-seeder, a moving body having impaling-pins thereon, a woven fabric, means for disposing the fabric with respect to the said moving body so that the impaling-pins first pass into and through the fabric and then out of engagement therewith, and means pressing the raisins to the pins to impale them thereon during the time that the fabric is engaged therewith, for the purpose specified.

5. A raisin-seeder, having a body carrying impaling-pins, a woven fabric, the said body and fabric being relatively movable to cause the pins to pass into and through the fabric and then out of engagement therewith, and means for impaling the raisins on the pins during the time that the pins are projected through the fabric, for the purpose specified.

In testimony whereof I have signed my name to this specification in the presence of two subscribing witnesses.

FRANK HENRY PETERMAN.
